UNITED STATES PATENT OFFICE.

THOMAS W. HARBER, OF SPRINGFIELD, MISSOURI.

WRENCH.

No. 904,954.

Specification of Letters Patent.

Patented Nov. 24, 1908.

Application filed March 22, 1907. Serial No. 363,840.

To all whom it may concern:

Be it known that I, THOMAS W. HARBER, citizen of the United States, residing at Springfield, in the county of Greene and State of Missouri, have invented certain new and useful Improvements in Wrenches, of which the following is a specification, reference being had therein to the accompanying drawing.

10 This invention relates to wrenches of that type in which a sliding adjustable jaw carries a lock-nut having distorted threads for engagement with like threads upon a shank carrying a rigid jaw.

15 It has for an object to provide a wrench of this type in which it is possible to secure an adjustment of the sliding jaw to any point between the limits of its adjustment.

Another object is to provide means for 20 preventing the lock nut being turned in the wrong direction.

With these and other objects in view, the invention consists of the parts and combinations of parts hereinafter to be described and 25 more particularly pointed out in the appended claims.

In the drawings, Figure 1 is a side view of the wrench. Fig. 2 is a longitudinal section. Fig. 3 is an edge view. Fig. 4 is a 30 section view of the lock-nut. Fig. 5 is a transverse section of the wrench through the lock-nut, showing the nut in locked position. Fig. 6 is a like view showing the nut in unlocked position.

35 Referring more particularly to the drawings, 1 indicates a shank having at one end a rigid jaw 2 which is preferably cast thereon. The other end of the shank carries a tapered tang 3 upon which is driven a wooden handle 4 which is strengthened at its ends by ferrules 5 and 6 respectively.

40 Slidable on the shank 1, is a movable jaw 7 which coöperates with the fixed jaw 2. This movable jaw 7 carries a pair of tongues 45 or projections 8 which extend into an annular groove 9 on a lock-nut 10 thus providing a rotatable connection between the nut and the shank. The lock-nut 10 surrounds the shank and is adapted to be interlocked 50 with said shank to hold the adjustable sliding jaw in various positions. This interlocking connection between the lock-nut and the shank comprises quarter segments 11 of screw threads on opposite faces of the shank, and quarter segments 12 of screw threads at 55 diametric points within the nut. That end

13 of each of the threads on the shank which is farther away from the fixed jaw or, in other words, those ends which are adjacent the entrance portions of the grooves between the threads are tapered. The entering ends 60 14 of the segmental threads within the nut, are also tapered. By this arrangement, it is impossible for the ends of the threads within the nut to engage the ends of the threads 65 on the shank.

When the sliding jaw is to be adjusted, the nut is turned so that the threads within the same, are out of engagement with the threads on the shank and lie opposite the 70 threadless portions of the shank. After the sliding jaw has been adjusted to the proper position, the nut is turned in the opposite direction and the tapered ends 14 will enter between the tapered ends 13 of the threads 75 on the shank. It is apparent that the tapered ends of the threads will permit the sliding jaw to be adjusted from one end of its adjustment to the other a distance equal to the thickness of a sheet of paper. 80

To prevent the lock-nut being turned in the wrong direction, I provide a rib 15 connecting the rear ends of the threads 12 within the lock-nut. This rib forms a stop to engage the rear ends of the threads on the 85 shank when the nut is turned in the wrong direction.

Having thus described my invention, what I claim and desire to secure by Letters-Patent is:

1. A wrench, comprising a shank, a fixed jaw at one end and a handle at the other, a sliding jaw adjustable on the shank and having a pair of overhanging hooks, a lock nut having an annular transverse flange to engage said hooks, threads extending partially around the end wall of said nut, said threads being connected by a rib, and segmental threads on said shank adapted to coöperate with the threads on said nut, the threads of 95 said nut and the threads of the shank having the same direction of pitch, whereby said threads will when rotated in one direction intermesh, the amount of rotation in said direction being limited by contact of said ribs 105 with said segmental threads.

2. A wrench, comprising a shank, a fixed jaw on one end, a handle on the other, a sliding jaw adjustable on the shank and having a pair of overhanging hooks, a lock nut having an annular transverse flange to engage said hooks, a series of threads on the 110

inner wall of said nut, a longitudinal rib integral with and connecting one end of said threads, segmental threads on said shank, said threads on said nut and said shank having the same direction of pitch whereby said threads on the nut and said shank will, when the nut is rotated in one direction, intermesh, the rotation in one direction being limited by contact of said rib with one end of said 10 segmental threads, the outer side of said rib being smooth and substantially normal to the inner wall of the nut whereby when said nut is rotated in the opposite direction, said outer side will touch the shank at the other end of said segmental threads and form a 15 line of contact.

In testimony whereof I hereunto affix my signature in presence of two witnesses.

THOMAS W. HARBER.
